(57) **CLAIM**

The ornamental design for a table, as shown and described.

DESCRIPTION

FIG. 1 is a perspective view of a table showing my new design;

FIG. 2 is a side elevational view, the opposite side being a mirror image thereof;

FIG. 3 is an end elevational view, the opposite end being a mirror image thereof; and,

FIG. 4 is a top view thereof.

The bottom view of the table is not shown and forms no part of the claimed design.

1 Claim, 4 Drawing Sheets

FIG. 1
